UNITED STATES PATENT OFFICE

ROBERT W. TIMMIS AND FRANK F. WILLIAMS, OF OAKLAND, CALIFORNIA; SAID WILLIAMS ASSIGNOR TO SAID TIMMIS

STERILIZER

Application filed October 7, 1930. Serial No. 486,940.

The invention relates to sterilizer apparatus utilizing a germicidal gas as a sterilizing agent therein.

An object of the invention is to provide a sterilizer of the class described which is designed for use without danger to an operator thereof.

Another object of the invention is to provide a sterilizer of the class described which is arranged to automatically perform certain functions after the receptacle thereof is sealed tight.

A further object is to provide a sterilizer wherein a non-gaseous charge of a vaporizable sterilizing agent is arranged to be gasified entirely within the sterilizing receptacle and by a controlled heating means. A more specific object is to provide a sterilizer of the class described which is particularly designed for use in sterilizing the apparatus handled by players of golf, particularly when such apparatus is to be used by more than one person.

The invention possesses other objects and features of advantage, some of which, with the foregoing, will be set forth or be apparent in the following description of typical embodiments of the invention, and in the accompanying drawings, in which:

30 Figure 1 is a perspective view of a sterilizer unit embodying the invention.

Figure 2 is a vertical side section through the unit.

Figure 3 is an enlarged vertical section 35 through charge-delivering mechanism of the device.

Figure 4 is a stepped plan section at 4—4 in Figure 2.

Figure 5 is a perspective view of an article-40 receiving basket of the sterilizer.

Figure 6 is a fragmentary perspective view of a golf club supporting means of the apparatus.

Figure 7 is a diagram of an electric heater 45 circuit of the sterilizer.

Figure 8 is a fragmentary sectional elevation of a modification of the sterilizer.

The embodiment of the invention illustrated in Figures 1 to 7 inclusive is particularly arranged for the sterilizing treatment

of golf clubs, golf balls, scoring pencils, and any other accessories which are handled by a player of golf. The apparatus is particularly designed for sterilizing the equipment which is handled by players at miniature 55 golf courses, the players at such courses generally using equipment not their own and which has been, and may thereafter be, used by others. Under the latter conditions, the need for sterilizing the apparatus after a 60 player is through with the same is obvious.

The features of the present invention are shown as applied to a sterilizing cabinet or receptacle 11 of rectangular outline, and having a cover 12 hinged thereto and arranged 65 for sealedly closing the top opening of the receptacle. As particularly shown, the cover sealing means comprises a gasket 13 extending around the cover for engagement with the frame of the top receptacle opening, and 70 toggle catches 14 are utilized for forcibly clamping the cover in place.

Means are provided for supporting various elements in the receptacle space for the sterilizing thereof. As shown, a golf club 75 supporting member 15 is provided at the top of the receptacle, said member comprising a wire grille horizontally disposed and having certain strands 16 thereof bent downwardly whereby cradles are provided for the heads 80 of golf clubs having their handles depending through and from the member 15, the supported relation of a club to the member 15 being indicated in Figure 2. By similarly offsetting certain sets of aligned strands, as 85 is brought out in Figures 2 and 6, the clubs may all be similarly disposed and a maximum use of the receptacle space is possible.

A porous basket 17 is provided for holding 90 golf balls, pencils, and other smaller articles in the sterilizer; as shown, said basket is of wire mesh construction and provides a pair of compartments 18 and 19 for the respective reception of balls and pencils. The member 15 and basket 17 may be supported in place 95 in any suitable manner; as indicated, these elements are arranged to rest on cleats provided on opposite walls of the cabinet and near the top thereof, one of said cleats being shown at 21 in Figure 2.

Obviously, sterilization by the application of a liquid agent to the articles to be sterilized is not practical, nor could steam be well used with non-metallic golf apparatus. The 5 present apparatus provides for a sterilization with a germicidal gas at substantially air temperature, said gas being freed in the closed receptacle. Preferably, and as shown, means are provided for generating 10 the gas within the receptacle, whereby the sterilizing unit is completely self-contained. Accordingly, an evaporating pan 22 is provided at, and centrally of, the bottom of the receptacle for receiving a charge of solid 15 or liquid material to be vaporized for providing a gaseous sterilizing agent in the cabinet, said material arranged to be one which may be vaporized by the application of heat thereto while it is in the pan 22.

20 An inexpensive and generally satisfactory sterilizing gas is that of formaldehyde, and in the present instance said gas is arranged to be generated by the application of heat to a solid form of formaldehyde such as trioxymethylene, or paraformaldehyde. The 25 formaldehyde generating material is preferably in the form of a ball or compressed mass 23 (Figure 3) for placement as a charge in the pan 22, and said pan is in the present 30 instance arranged to be heated by means of an electrical heating unit 24 associated therewith.

Means are provided for effecting a controlled delivery of a charge 23 to the pan 22 35 when and as required. As shown, such means comprises the provision of a tubular duct 20 extending downwardly along a receptacle corner and to the pan, the inlet of said duct being adjacent the top of the cabinet to facilitate placement of a charge therein. A 40 shutter or gate 25 is provided in and across the upper duct end, said shutter normally operative to retain the charge 23 thereabove, as is shown in Figure 3. The shutter 25 comprises a plate slidably engaged in a transverse slot through the duct 20 and through a slot in the adjacent cabinet wall. Suitable 45 gas-tight packing 26 is provided where the shutter 25 extends through the cabinet wall, and a pull handle 27 is provided at the outer shutter end. A spring 28 urges the shutter to maintain its operative and inward position, and a manual displacement of the shutter by use of the handle 27 is arranged to 50 permit the escape of the charge 23 through the registration of a shutter opening 29 with the duct bore. In this manner, the charge 23 may be released from without the cabinet when the latter is completely closed.

55 Means are provided whereby a closing of the cover 12 effects an energization of the heating unit 24. Accordingly, and as shown, a switch 31 is provided for closure by the cover 12 when the latter is in closed position. The circuit of the switch 31 and heat-

ing unit 24 also preferably includes an automatic circuit-breaking time switch 32, the latter preferably being of a temperature controlled type whereby the heater circuit is arranged to be opened after a predetermined time of operation thereof. A signal lamp 33 may also be included in the heater circuit, said lamp mounted on a cabinet wall, and arranged to be lit only while the heater is energized whereby an operator may be advised of the operative condition of the sterilizer. It is noted that the actual temperature of the generated gas is substantially that of the atmosphere.

It will now be understood that when the sterilizer is to be used, the articles to be sterilized are placed in the cabinet, and a charge 23 placed in the duct 20 to rest on the shutter 25. The cover 12 is now closed whereby to seal the cabinet and close the switch 31 for energizing the heater unit 24. The shutter is manually displaced to release the charge 23 therefrom, said charge falling and rolling through the duct to the pan 22 where it is vaporized. A screen 34 covers the pan 22 to insure the retention of the charge therein, and a perforated baffle plate 30 is provided above and adjacent the pan for insuring an even distribution of the generated gas to the cabinet space.

When sterilization is completed, the sterilizing gas is arranged to be flushed from the cabinet without opening the latter. Accordingly, a discharge opening 35 is provided in the upper cabinet portion, while an air inlet opening 36 is provided in the lower cabinet portion. As shown, the openings 35 and 36 are diagonally related, and the opening 35 communicates with a valved vent duct 37 which may discharge where desired. During 100 sterilization, the valve 38 of the duct 37 is, of course, closed, and a door 39 at the opening 36 is also closed. Opening of the valve 38 and door 39 is arranged to effect a rapid air flushing of the cabinet, after which the cover 105 12 may be opened and the sterilized objects removed, an operator being at no time exposed to the sterilizing fumes. Said flushing may be entirely by convection, and a suction fan (not shown) may be provided to supplement the convection discharge of the gas.

Where electric power is not available or desired for providing the vaporizing heat, an arrangement such as is shown in Figure 8 may be utilized. In this instance, a pan 81 is provided for receiving a pellet of potassium permanganate, or other chemical which produces heat when water is applied thereto. A tube 82 corresponding to the duct 24 of the first embodiment delivers the potassium permanganate pellet to the pan 81 from the cabinet top. A second tube 83 slopes to the pan 81 from without the cabinet, said tube having a cap 84 normally sealing its outer end. The introduction of an aqueous solution of form-

aldehyde (said solution being known as formalin) into the pan containing the potassium permanganate charge produces the heat necessary to evaporate the formaldehyde for filling the cabinet 85 with formaldehyde gas.

It will, of course, be obvious, that other gases than formaldehyde may be generated and used in the now described sterilizer apparatus.

10 From the foregoing description taken in connection with the accompanying drawings, the advantages of the construction and method of operation will be readily understood by those skilled in the art to which the invention appertains, and while we have described the principle of operation, together with the device which we now consider to be the best embodiment thereof, we desire to have it understood that the device shown is 15 merely illustrative, and that such changes may be made, when desired, as fall within the scope of the appended claims.

Having thus described our invention, we claim as new and desire to secure by Letters 25 Patent of the United States the following:

1. In a sterilizer, a receptacle, a cover for effecting a sealed closure of the receptacle space, an evaporation cup in the said space and arranged to receive a charge of a vaporizable chemical sterilizing agent, means to heat said cup, and means to deliver a said charge of the sterilizing agent to said cup while said cabinet is sealed completely.

2. In a sterilizer, a sealable sterilizing receptacle, an evaporation cup in said receptacle and arranged to receive a charge of a vaporizable chemical sterilizing agent, means for gasifying a said charge in said cup, means for releasably retaining said charge 30 in said receptacle and spaced from said cup, means to guide the released said charge to said cup, and means actuatable from without the receptacle and while the same is completely sealed to render said charge-retaining means inoperative.

3. In a sterilizer, a sealed receptacle having a removable closure member at the top thereof, an evaporation cup at the bottom of said receptacle and arranged to receive a 40 charge of vaporizable chemical sterilizing agent, means to heat said cup for gasifying said charge, a tube extending entirely within said receptacle and from the top portion thereof to said cup for conveying a said charge thereto, a shutter in said tube adjacent the upper end thereof and normally disposed to retain a said charge thereon and in the tube, and means operative from without the receptacle to displace said shutter for releasing a said charge thereon.

4. In a sterilizer cabinet, a closure member for effecting a sealed closure of the cabinet space, an evaporation cup in said receptacle and arranged to receive a charge of a vaporizable chemical sterilizing agent, an elec-

trical heating unit to heat said cup, an electric switch arranged to be closed by and upon the operative disposal of said closure member, a normally closed time switch operative independently of the temperature in 70 the cabinet and arranged to automatically open following a flow of electric current therethrough for a predetermined and fixed time interval, and an electric circuit including said unit and switches in series connection.

5. In a sterilizer, a sealed receptacle having a displaceable closure member at the top thereof, an evaporation cup at the bottom of said receptacle and arranged to receive a charge of a normally solid and vaporizable chemical sterilizing agent, means to heat said cup for gasifying a said charge therein, a conveyor tube extending from said cup and upwardly within said receptacle to a point adjacent the top thereof whereby to facilitate the placement of a said charge therein from the top opening of the receptacle when said closure member is displaced, a shutter in said tube adjacent the upper tube end and normally disposed to retain a said charge thereon and in the tube, and means operative from without the receptacle to displace said shutter for releasing a said charge therefrom while said closure member is operatively disposed.

In testimony whereof, we affix our signatures.

ROBERT W. TIMMIS.

FRANK F. WILLIAMS.
